UNITED STATES PATENT OFFICE

2,084,331

SEAMLESS PIPE OR TUBE MILL

Stevenson Findlater, McKeesport, Pa., assignor
to National Tube Company, a corporation of
New Jersey

Application November 21, 1934, Serial No. 754,169

4 Claims. (Cl. 80—13)

This invention relates to improvements in seamless pipe or tube mills, and more particularly to means for automatically compensating for the expansion of the mandrel bar.

In the manufacture of seamless pipes and tubes, considerable difficulty has been encountered in maintaining constant the distance between the surfaces of the various rolls of the mill and the surfaces of the mandrel plug, such as is commonly used in piercing, expanding, elongating, reducing, etc., operations. While this condition can be attributed somewhat to the expansion of the rolls and mandrel plug, it is largely due to the expansion of the mandrel bar supporting the plug in the roll pass. That is to say, as the rolls and mandrel plug of the mill acquire heat from the work-piece being processed they will, of course, expand, causing their surfaces to become closer to one another. As the mandrel bar becomes hotter, acquiring heat from the work-piece being processed, it will increase in length and accordingly move the surfaces of the mandrel plug nearer to the rolls of the mill. This moving together of the various metal working surfaces of the mill causes the wall thickness of the work-piece being processed to vary, due to a more substantial reduction in the wall of the work-piece when the mandrel bar, rolls and mandrel plug are hot than would be the case were they cold.

The temperature of a seamless pipe or tube mill is usually no higher at the end of a long period of operation than it was at the beginning. This is for the reason that the mill is started without cooling water on the rolls and heated billets passed therethrough until the rolls acquire a desired temperature. At this time the rolls are sprayed with water in order that the temperature will not rise greatly beyond that desired. In this manner the general temperature of the mill is maintained as desired; but as each highly heated billet, or work-piece, moves through it, the temperature of the mill elements is temporarily raised. This temporary rise in temperature causes a correspondingly temporary expansion, particularly of the mandrel bar; the effects of which the present invention seeks to avoid.

In a copending application entitled "Apparatus for making tapered tubular work-pieces" filed December 29, 1934, Serial No. 759,804, I have disclosed apparatus which is in many respects similar to that disclosed herein. This copending application is, however, concerned with making a tubular work-piece which is tapered in both inside diameter and wall thickness.

One object of the present invention is to provide novel and automatically actuated means for compensating to exactness the expansion of the mandrel bar and rolls of the mill, and maintaining constant the distance between the surfaces of the various rolls of the mill and the surfaces of the mandrel plug, resulting in elimination of variations from the desired wall thickness of the work-piece.

Another object of the invention is to provide novel and automatically actuated mechanism, operating under a heavy thrust, for slowly withdrawing the mandrel bar of a seamless tube mill in exact ratio to the expansion of the mandrel bar and of the rolls in the mill, resulting in a constantly maintained distance between the various metal working surfaces, together with automatically actuated mechanism for rapidly returning the mandrel plug to its initial position.

A further object is to regulate the relative positions of the mandrel plug to the various metal working rolls, even when the mill is cold, in accordance with the temperature of the work-piece, and thus compensate for differences in resistance to metal displacement caused by introducing metal of varying temperature into the mill.

A still further object is to provide novel apparatus of the class described which can be installed on existing mills with but little modification and expense.

These and further objects of the invention will appear after referring to the drawings, in which:

Figure 1 is a fragmentary plan of a conventional pipe or tube mill.

Figure 2 is a fragmentary plan of the apparatus of the invention.

Figure 3 is a sectional view on the line III—III of Figure 2.

Figure 4 is a view on the line IV—IV of Figure 3.

Figures 5 and 6 are electrical circuits for operating the various elements of the invention.

Referring to Figure 1 of the drawings, there is disclosed a conventional seamless pipe or tube mill of the well known Stiefel type, comprising a pair of cone-shaped metal working rolls A between which there is disposed a mandrel plug B. In this figure of the drawings one of the cone-shaped metal working rolls A is shown as being motivated by a suitable electric motor 58, while the other metal working roll A may be driven by a similar device or, if desired, from the same motor through suitable gearing. It is not believed necessary to illustrate either mode of

operation of the second metal working roll A, and such is therefore omitted for the sake of simplicity.

Referring to Figure 2 of the drawings, the numeral 2 designates a support for the apparatus of the invention. A mandrel bar carriage 3 is mounted on the support 2 for sliding movement therewith, in order to adjustably position a mandrel bar 4, and its associated mandrel plug B with respect to the rolls A of the conventional seamless tube mill. The end of the mandrel bar 4 is secured to the carriage 3 in any suitable manner as, for example, by a coupling 4a on the extension 3a of a thrust bearing located immediately at the rear thereof.

A support 5 is pivoted to the frame 2, as at 5a, and provided with a horizontally disposed shaft 6 adjacent the upper surface of the mandrel bar carriage 3. A pair of links 8 is secured to the shaft 6 and is adapted, by suitable mechanism, to move the support 5 above the pivot 5a.

A motor 9 is secured to the frame 2 and provided with the usual motorshaft 9a and coupling 10, for connecting the same to a shaft 11a of a gear reduction mechanism generally indicated at 11. The gear reduction 11 is provided with another shaft 11b and a coupling 12 for connection to a shaft 13 which is journaled in a bearing 14. A magnetic clutch 15 is disposed adjacent the bearing 14 for clutching-in a shaft 16. A worm 17 is mounted on the shaft 16 for rotating a worm gear 24. The worm gear 24 is provided with a suitably journaled elongated sleeve portion 24a, on which it is mounted. The elongated sleeve portion 24a is internally screw-threaded for engagement with a screw 25, which is secured to one of the links 8 by a pin 25a. The other end of the shaft 16 is provided with a coupling 18 to which there is secured a shaft 19 on which there is mounted a worm 20. The shaft 19 is secured at its other end to the shaft 23a of a motor 23, by means of a coupling 21.

The worm 20 is adapted to cooperate with a worm gear 26 which is mounted on a suitably journaled elongated sleeve 26a. The elongated sleeve 26a is internally screw-threaded to receive a screw 27, which is secured to the free end of the other of the links 8 by a pin 27a.

A magnetic brake 28 is provided for the motor 23. A latch 7 is secured to the horizontal shaft 6 and is adapted to make contact on its outer end with a wear-plate 3b which is secured to the mandrel bar carriage 3.

The horizontal shaft 6 and latch 7, which is secured thereto, are adapted to be partially rotated by means of a rod 7a, which is secured to the shaft 6 at one of its ends in a suitable manner, and to the piston of an air cylinder 7a at its other end.

A suitable and conventional electrical wiring circuit including a pyrometer device, relays, and preferably also push-buttons, is provided for the motors 9 and 23, the magnetic clutch device 15 and the magnetic brake 28 for the motor 23.

The rotation of the motor 9 is automatically compensated for differences in the resistance to metal displacement caused by introducing metal of varying temperatures into the rolls. The operation is such that the variations in temperature of the work-piece being processed, as measured by photoelectric, optional radiation or other pyrometer, will be transmitted to the motor 9 in such manner as to increase or retard the rotation thereof, thereby varying the rate at which the compensator operates.

In operation, upon the entry of a pipe or tube into the rolls A of the mill, the motor 9, magnetic clutch 15 and magnetic brake 28 are energized through the load relays, or suitable push-buttons described. As before stated, the rate at which the motor operates is controlled through suitable resistance, modified by the action of the pyrometer. The motion transmitted by the motor 9, gear reduction 11 and shaft 16, through the magnetic clutch 15, is transmitted to the worm 17, coupling 18 and, by means of shaft 19, the worm 20. The worms 17 and 20 will rotate the worm gears 24 and 26, and their respective sleeves 24a and 26a. The action will cause the screws 25 and 27 to draw the links 8 and attached support 5 backward, or away from the mill, and accordingly permit the same movement of the mandrel bar 4 and the plug B on the other end thereof. A tendency of the plug, mandrel bar and mandrel bar carriage to move backwardly will, of course, be caused by the action of the work-piece in the mill. This motion will be slowly permitted, as determined by the suitable resistance described, until the work-piece has passed through the mill.

The rotation of the shaft 16, which is transmitted to the shaft 19 by means of the coupling 18, will cause the shaft 23a of the motor 23 to rotate idly, when the motor 9 is energized to withdraw the mandrel bar carriage.

After the work-piece has passed through the mill, the mandrel bar carriage and attached mandrel bar must be quickly returned in order to position the mandrel plug (not shown) in its initial position in the mill, before the next tube or work-piece is introduced into the rolls A.

The operator attending the device, or a suitable relay, momentarily energizes the magnetic brake 28 for the motor 23. This operation at the same time instantaneously deenergizes the magnetic clutch 15 and disengages the motor 9. The motor 23 is then actuated to reverse the direction of rotation of the worms 20 and 17 to rapidly return the support 5 to position preparatory to rolling the next work-piece. At the proper and predetermined position, the action of the motor 23 is arrested by a suitable limit switch, which also applies the brake 28 for the motor 23.

As before stated, the motor 23 will rotate when the action of the motor 9 withdraws the mandrel bar carriage but, upon the return stroke of the carriage, when the motor 23 is energized, the magnetic clutch 15 is deenergized, preventing rotation of the gear reduction, generally indicated at 11, and the motor 9.

Referring to Figures 5 and 6 of the drawings, I have disclosed in a diagram one form of electrical control which will function to operate the elements of the invention in the manner previously described. In this diagram the numerals 30 and 31 designate suitable power lines carrying normal voltage; such as 220 volts.

In order to satisfactorily control the operation of the motor 9, a wire 33 is connected between the power lines 30 and 31, and includes a starting switch 34 and a coil 35. A line 36 connects the line 33, between the power line 31 and the starting switch 34, to the line 33, between the starting switch 34 and the coil 35.

This line 36 includes a manually operable stopping switch 38 and a pair of contacts 35a which are operated by the coil 35. A line 39 connects the line 33, between the contacts 35a and the line 33, with the line 33 between the coil 35 and the power line 31. This line includes a coil 40 and a pair of contacts 35b, the latter also

being operated by the coil 35. A line 41 is connected to the line 36, between the contacts 35^a and the line 33, and to the line 39 between the coil 40 and the contacts 35^b. This line 41 has included in its circuit a pair of coils 42 and 43 and an auxiliary magnetic switch 44.

The motor 9 is connected between the power lines 30 and 31 by a line 46 which includes two pairs of contacts, as at 42^a and 43^a, which are operated by the coils 42 and 43, respectively. This line 46 also includes a pair of contacts 40^a between the power line 30 and the motor 9, and a pair of contacts 40^b between the contacts 42^a and 43^a and the power line 31. The contacts 40^a and 40^b are operated by the coil 40 and likewise the auxiliary contacts 44.

The photoelectric pyrometer device, which is generally indicated at X, is connected by a line 48 with a series of relays 49, 50, 51, 52, 53 and 54. These relays form a part of a field rheostat 55 which effects an automatic speed adjustment for the motor 9. Each of these relays is adjusted to trip at a definite temperature. This field rheostat 55 is connected between the power lines 30 and 31 by a line 56. This line 56 has included therein, between the power line 30 and the field rheostat 55, the shunt field for the motor 9, which is designated at 9^a, and a hand-operated rheostat 57.

Referring to Figure 5 of the drawings, it is to be noted that the motor for rotating the usual metal working rolls is diagrammatically shown at 58, being connected by a line 59 between suitable power lines 60 and 61. While one motor 58 is illustrated in the drawings and may be employed to drive both of the metal working rolls through the medium of suitable gearing (not shown), the invention also contemplates the driving of each roll with an individual motor. The motor 58 is continuously driven as long as the mill is operating. The power lines 60 and 61 supply the motor 58 with current of a considerably higher voltage than that furnished through the power lines 30 and 31; as, for instance, 600 volts. A shunt 65 is included in the line 59 between the power line 60 and the motor 58. A pair of lines 66 and 67 connect the shunt 65 with a load relay 68. The magnetic clutch 15 which is carried on the shaft 16 is connected between the power lines 30 and 31 by a line 70, which has included therein two pairs of contacts, as at 68^a and 68^b, one on either side of the magnetic clutch. The magnetic brake 28 is connected by a line 71 with the power lines 30 and 31 and includes in its circuit two pairs of contacts, as at 68^c and 68^d. A line 73 is connected to the line 70 between the power line 30, and the contacts 68^a, and to the line 71 between the contacts 68^c and the magnetic brake 28. This line 73 includes a pair of contacts 68^e. A similar line 74 is connected to the line 70 between the power line 31 and the contacts 68^b, and to the line 71 between the contacts 68^d and the magnetic brake 28. This line 74 carries a pair of contacts 68^f.

In order to satisfactorily control the operation of the motor 23 which functions to rapidly return the mandrel bar carriage to its initial position, a line 77 is connected between the power lines 30 and 31 and has included therein a starting switch 78, a limit switch 79 and a coil 80. A line 81 connects the line 77, between the power line 30 and the starting switch 78 with the line 77 between the starting switch 78 and the limit switch 79. This line 81 includes a stopping switch

83, and a pair of contacts 80^a, the latter being operated by the coil 80.

A line 84 connects the line 81 between the contacts 80^a and limit switch 79 with the line 77 between the coil 80 and the power line 31. The line 84 has included in its circuit a pair of coils 85 and a pair of contacts 80^b, the latter being operated by the coil 80. A line 87 is connected to the line 81 between the contacts 88 and the limit switch 79, and to the line 84 between the coils 85 and the contacts 80^b. This line 87 includes in its circuit a pair of coils 88, 89 and an auxiliary switch 85^c, the latter being operated by the coils 85.

The coils 85 of the line 84, in addition to operating the auxiliary magnetic switch 85^c, also operate the contacts 85^e and 85^b in the line 71.

The motor 23 is connected between the power lines 30 and 31 by a line 90 which has included therein a pair of contacts 88^a and 89^a which are operated by the coils 88 and 89, respectively, of the line 87. A pair of contacts are disposed in the line 90 between the motor 23 and the power line 30 as indicated at 85^c; while a similar pair of contacts 85^d are disposed in the line 90 between the power line 31 and the contacts 88^a and 89^a.

A line 91 is connected between the power lines 30 and 31 and includes the shunt field for the motor 23, which is designated at 23^a, and a hand-operated rheostat 93.

The energization of the load relay 68 closes the contacts 68^a and 68^b in the line 70, and the contacts 68^c and 68^d in the lines 73 and 74, respectively.

The limit switch 79 is arranged in such manner as to be opened by the movement of the mandrel bar carriage 3 to its original position in the mill, prior to the processing of a work-piece.

In operation: The operator of the mill closes the starting switch 34 for the motor 9, thus energizing the coil 35 (which is maintained by its contacts 35^a), thus closing the contacts 35^a and 35^b and energizing the coil 40 to close the contacts 40^a and 40^b. The closing of these contacts and the contacts of the auxiliary switch 44, which they effect, starts the motor 9 which will attain a speed of rotation which is predetermined by the setting of the hand-operated rheostat 57. The closing of the contacts of the auxiliary switch 44 energizes the coils 42 and 43, thus closing the contacts 42^a and 43^a.

As the work-piece (not shown) enters the mill, the power required by the motor 58 in driving the metal working rolls passes through the shunt 65. This causes a "voltage drop" across the shunt, and energizes the load relay 68, which causes the closing of the contacts 68^a, 68^b, 68^c and 68^d. The closing of these contacts energizes the magnetic clutch 15, and the magnetic brake 28. The accompanying coupling of the clutch and the release of the brake mechanically connects the motor 9, which is running, as previously mentioned. The motor 9 withdraws the mandrel bar carriage 3 of the mill at a speed which is predetermined by the setting of the hand-operated rheostat 57.

The photoelectric pyrometer device, which is generally designated at X, is set for a predetermined temperature indication, and if the temperature of the work-piece as it passes the point upon which it is "trained", is either above or below this indication, the relays 49 through 54, inclusive, are individually and progressively excited and caused to function. The functioning of these relays will include, or delete, sections

of the field rheostat 55 to increase, or decrease, the speed of operation of the motor 9. It will thus be seen that the rate of withdrawal of the mandrel bar carriage 3 is in direct proportion 5 to the temperature of the work-piece being processed in the mill. That is to say, the size of the pass will remain constant regardless of variations resulting from expansion of the mandrel plug and rolls, which is, in turn, due to temperature changes. These changes in temperature 10 take place upon the entry into the mill of each highly heated work-piece.

The power required by the motor, or motors, 15 58 which drives the metal working rolls of the mill will approach zero after the trailing end of the work-piece has emerged therefrom. This causes the "voltage drop" across the shunt 65 to approach zero, and in consequence thereof the deenergization of the load relay 68. The deenergization of this load relay opens the contacts 68^a, 68^b, 68^c and 68^d, to deenergize the magnetic clutch 15 and the magnetic brake 28. This last 20 operation uncouples the clutch and applies the brake to stop the motor 9.

25 After the operator has removed the work-piece from the mill from the usual discharge trough (not shown) and returns the mandrel bar to the usual position, he operates the starting switch 78 for the motor 23.

30 The operation of the starting switch 78 for the motor 23 energizes the coil 80 (which is maintained by one of its contacts 80^a), and closes the contacts 80^a and 80^b; thus energizing the coils 85. The energization of the coils 85 closes the contacts 85^a, 85^b, 85^c and 85^d and the contacts of 35 the auxiliary switch 85^e to energize and release the magnetic brake 28 and start the motor 23.

35 The speed attained by the motor is predetermined by the setting of the hand-operated rheostat 93, after the closing of the contacts of the auxiliary switch 85^e. The closing of the auxiliary switch 85^e energizes the coils 88 and 89, which close the contacts 88^a and 88^b.

40 The motor 23 will operate to return the mandrel bar carriage 3 to its original position in the mill, which is predetermined by the location of the limit switch 79, the latter opening when this position is reached. The opening of this limit switch deenergizes the coil 88, thus opening the contacts 88^a and 88^b, thereby stopping the operation 45 of the motor 23 and effecting the application of the magnetic brake 28, all by the opening of the various contacts 85^a, 85^b, 85^c and 85^d, and the contacts of the auxiliary switch 85^e, which is caused by the deenergization of the coils 85.

45 The equipment is now ready for another cycle of operation, which is effected by the entry of a second work-piece between the rolls of the mill which are driven by the motor 58. This effects 50 a second "voltage drop" across the shunt 65, which energizes the load relay 68, thus repeating the operation previously described.

55 While I have shown and described certain specific embodiments of my invention, it will be understood that I do not wish to be limited exactly thereto, since various modifications may be made without departing from the scope of my invention, as defined by the following claims.

I claim:

1. A seamless pipe or tube mill comprising in combination, at least one power actuated metal working roll, a roll for coating with said first named roll, a movable carriage, a mandrel bar connected to and extending from said movable carriage, a mandrel plug carried on the extended end of said mandrel bar, said mandrel plug being adapted for disposal intermediate said rolls, means for moving said carriage away from said rolls 10 while a pipe or tube is being acted upon by said rolls and said mandrel plug, whereby the position of said mandrel plug is adjusted with respect to said rolls, means responsive to the temperature of said pipe or tube for modifying the rate of 15 speed of said last named means, and means for returning said carriage to its initial position.

2. A seamless pipe or tube mill comprising, in combination, at least one power actuated metal working roll, a roll for coating with said first named roll, a movable carriage, a mandrel bar connected to and extending from said movable carriage, a mandrel plug carried on the extended end of said mandrel bar, said mandrel plug being adapted for disposal intermediate said rolls, a 20 support adjacent said carriage, means on said support for making contact with said carriage, means for moving said support away from said rolls while a pipe or tube is being acted upon by said rolls and said mandrel plug, said last named 30 means permitting said carriage to likewise move away from said rolls, whereby the position of said mandrel plug is adjusted with respect to said rolls, means responsive to the temperature of said pipe or tube for modifying the rate of speed 35 of said last named means, and means for returning said support and said carriage to their initial positions.

3. A seamless pipe or tube mill comprising, in combination, at least one power actuated metal 40 working roll, a roll for coating with said first named roll, a mandrel bar, a mandrel plug carried by said mandrel bar, said mandrel plug being adapted for disposal intermediate said rolls, means for withdrawing said mandrel plug from said rolls 45 to maintain a desired relationship between the surfaces of said mandrel plug and said rolls while a pipe or tube is being acted upon thereby, means responsive to the temperature of said pipe or tube for controlling the speed of operation of said 50 withdrawing means, and means for returning the withdrawn mandrel plug to its initial position.

4. A seamless pipe or tube mill comprising, in combination, at least one power actuated metal working roll, a roll for coating with said first named roll, a mandrel bar, a mandrel plug carried by said mandrel bar, said mandrel plug being adapted for disposal intermediate said rolls, means for withdrawing said mandrel plug to compensate 55 for expansion and maintain substantially constant the distance between the surfaces of said mandrel plug and said rolls while a pipe or tube is being acted upon thereby, means responsive to the temperature of said pipe or tube for controlling the speed of operation of said withdrawing means, 60 and means for returning the withdrawn mandrel plug to its initial position.

STEVENSON FINDLATER.
